ABSTRACT

Substituted dibenz[a,h]azulenones and 8-(oxa or thia) substituted dibenz[a,h]azulenones, e.g., 6,7-dihydro-benz[b]indenod[1,2-d]thiepin-8(8H)-one, prepared by treating a substituted spiro[1-benzoxa or thia-5(4H)-1'-isobenzofuran]-3'-one with concentrated mineral acid. The compounds are useful as anti-depressants.

4 Claims, No Drawings

SUBSTITUTED DIBENZ[A,H]AZULENONES AND
8-(OXA OR THIA) SUBSTITUTED DIBENZ[A,H]
AZULENONES

This invention relates to dibenz[a,h]azulenones and 8-(oxa or thia)dibenz[a,h]azulenones. More particularly, it relates to substituted dibenz[a,h]azulenones and 8-(oxa or thia)substituted dibenz[a,h]azulenones, intermediates thereof and processes for their preparation.

The compounds of this invention may be represented by the following structural formula: 10

wherein

R₁ is hydrogen, halo having an atomic weight of 19 to 36, or lower alkoxy having one to four carbon atoms, e.g., methoxy, ethoxy, propoxy, isopropoxy, butoxy or isobutoxy;

R₂ and R₄ are independently, hydrogen, lower alkyl having one to four carbon atoms, e.g., methyl, ethyl, propyl, isopropyl, butyl or isobutyl, lower alkoxy having one to four carbon atoms, e.g., methoxy, ethoxy, propoxy, isopropoxy, butoxy or isobutoxy, or trifluoromethyl;

R₃ is hydrogen, halo having an atomic weight of 19 to 36, lower alkyl having one to four carbon atoms, e.g., methyl, ethyl, propyl, isopropyl, butyl or isobutyl, lower alkoxy having one to four carbon atoms, e.g., methoxy, ethoxy, propoxy, isopropoxy, butoxy or isobutoxy, or trifluoromethyl;

R₅ and R₈ are independently hydrogen, halo having an atomic weight of 19 to 36, or lower alkyl having one to four carbon atoms, e.g., methyl, ethyl, propyl, isopropyl, butyl or isobutyl;

R₆ and R₇ are independently, hydrogen, halo having an atomic weight of 19 to 36, lower alkyl having one to four carbon atoms, e.g., methyl, ethyl, propyl, isopropyl, butyl or isobutyl or lower alkoxy having one to four carbon atoms, e.g., methoxy, ethoxy, propoxy, isopropoxy, butoxy or isobutoxy;

R₁ and R₂ or R₂ and R₃ or R₃ and R₄ together are methylenedioxy;

R₅ and R₆ or R₆ and R₇ or R₇ and R₈ together are methylenedioxy; and

X is -CH₂-, S or O;

provided that

1. maximum number of substituents on ring A and/or D is two, and

2. there are no adjacent trifluoromethyl groups.

The process for preparing the compounds of formula (I) may be represented by the following reaction scheme A.

wherein R₁, R₂, R₃, R₄, R₅, R₆, R₇, R₈ and X have the above-stated significance.

The compounds of formula (I) are prepared by treating a compound of formula (II) with a concentrated mineral acid such as sulfuric acid or phosphoric acid, (sulfuric acid is preferred) at a temperature of from about -20° to 10° C. preferably from -10° to 0° C. for about 10 to 15 hours, preferably about 12 hours. The temperature used are not critical. The compounds of formula (I) may be recovered using conventional recovery techniques such as crystallization.

The compounds of formula (II) may be prepared by the following reaction scheme B:

wherein R_1 , R_2 , R_3 , R_4 , R_5 , R_6 , R_7 , R_8 and X have the above-stated significance.

The compounds of formula (II) and formula (III) are prepared by treating a compound of formula (V) with a compound of formula (IV) in the presence of an inert gas, in an inert solvent such as diethyl ether, tetrahydrofuran, hexane, heptane, benzene and the like and subjecting the reaction mixture to hydrolysis, preferably with aqueous ammonium chloride. This is represented by reaction scheme b₁. The reaction may be carried out at a temperature of from about -80° to -20° C., preferably -60° to -40° C. for about 1 to 3 hours. Compound (IV) is preferably added in inert solvent (as described above) to a cold (-60° to -40° C.) inert solvent solution of compound (V). The solvents and the temperature used are not critical. Compounds (II) may be separated from compounds (III) by conventional means such as filtration and/or crystallization.

Compounds (III) may be converted into compounds (II) by subjecting the reaction mixture of compounds (II) and (III) from scheme b₁ in a solvent as described in process b₁, to a temperature of from 60° to the reflux temperature of the solvent, preferably from 100° to 120° C. for 15 to 48 hours, preferably 24 hours. This is represented by reaction scheme b₂.

Alternatively compounds (III) may be separated (as described above) from compounds (II) and treated as described in scheme b₂.

Neither the solvents nor the temperatures used are critical. The compounds of formulas (II) and (III) may be recovered using conventional recovery techniques such as crystallization.

Certain of the compounds of formula (V) are known and may be prepared by methods disclosed in the literature, e.g., by the following reaction scheme C:

wherein R_1 , R_2 , R_3 and R_4 have the above-stated significance and R_9 is lower alkyl having 1 to 4 carbon atoms, e.g., methyl, ethyl, propyl, isopropyl, butyl or isobutyl.

The compounds of formula (V) are prepared by treating a compound of formula (VI) with an organolithium compound of formula (VII) in an inert solvent (as described in reaction scheme b₁) in the presence of an inert gas at a temperature of from about -10° to 10° C., preferably -5° to 5° C. for about 1 to 3 hours. The solvents and the temperatures used are not critical.

Certain of the compounds of formulas (IV), (VI) and (VII) are known and may be prepared according to methods disclosed in the literature. Those compounds of formulas (IV), (VI) and (VII) not specifically disclosed are prepared according to analogous methods from known materials.

The compounds of formula (I) are useful because they possess pharmacological activity in animals. In particular, the compounds possess central nervous system activity and can be used as anti-depressants as indicated by their activity in the mouse in reversing

reserpine hypothermia (spencer, P.S.J., antagonism of Hypothermia in the Mouse by Anti-depressants, in Anti-depressant Drugs, p. 194 - 204, Eds., S. Garattini and N.N.G. Dukes, Excerpta Medica Foundation, 1967).

The compounds may be administered orally or parenterally.

The dosage administered will vary depending on the particular compound employed, the therapy desired and the severity of the condition being treated. In general, satisfactory results are obtained when the compounds are administered at a daily dosage of from about 1 - 30 mg/kg of animal body weight, preferably given in divided dosages, 2 to 4 times a day or in sustained release form. For most larger mammals (e.g., primates) the total daily dosage is from about 20 milligrams to about 100 milligrams. Dosage forms suitable for internal use comprise from about 5 milligrams to about 50 milligrams of the active compound in intimate admixture with a solid or liquid pharmaceutically acceptable carrier or diluent.

A representative formulation suitable for oral administration is a capsule prepared by standard techniques which contain the following:

	Ingredients	Parts by Weight
30	6,7-dihydro-benz[b]indeno[1,2-d]thiepin-8(8H)-one Inert filler (starch, kaolin, lactose etc.)	25 275

EXAMPLE I

6,7-dihydro-benz[b]indeno[1,2-d]thiepin-8(8H)-one

Step 1 - 2,3-dihydro-spiro[1-benzothiepine-5-(4H)-1'-phthalan]-3'-one and o-(2,3,4,5-tetrahydro-5-hydroxy-1-benzothiepin-5-yl)

To a flask equipped with a stirrer, dropping funnel, condenser and gas inlet tube and maintained under a nitrogen atmosphere there was added at room temperature 3.8 g (0.027 mole) N-methyl benzamide and 75 ml anhydrous tetrahydrofuran. The reaction flask was immersed in an ice bath and cooled to an internal temperature of 5°. Stirring was initiated and 38 ml of 15% n-butyl lithium (0.06 mole) in hexane was added dropwise in about 40 minutes maintaining the temperature below 8°. The resulting N-methylbenzamide lithium adduct was stirred at 5° for 1 hour longer and then the reaction flask was immersed in a dry-ice acetone bath and cooled to an internal temperature of -60°. To the cold reaction mixture a solution of 5.35 g (0.03 mole) of 3,4-dihydro-1-benzothiepin-5-(2H)-one in 30 ml anhydrous tetrahydrofuran was added dropwise in about 30 minutes maintaining the temperature between -60° to -5°. The resulting adduct was stirred at -60° for 1 hour and then allowed to warm to 0° in about 1 hour and then treated with 35 ml saturated ammonium chloride. The layers were separated and the organic phase was washed once with 30 ml saturated ammonium chloride, dried over anhydrous Mg_2SO_4 and evaporated in vacuo. The resulting oil was triturated with ether and the o-(2,3,4,5-tetrahydro-5-hydroxy-1-benzothiepin-5-yl)-N-methyl benzamide, mp 128 to

130° C. was removed by filtration. The filtrate was evaporated in vacuo and the oil was crystallized from ether to give 2,3-dihydro-spiro[1-benzothiepin-5(4H)-1'-phthalan]-3'-one, m.p. 119°-121° C.

Step 2 - 6,7-dihydro-benz[b]indeno[1,2-d]thiepin-8(8H)-one

300 mg (0.00106 mole) 2,3-Dihydro-spiro[1-benzothiepin-5(4H)-1'-phthalan]-3'-one was added in portions to 10 ml concentrated H₂SO₄ at 0° the resulting solution was kept at 5° for 15 hours. At the end of this time the reaction mixture was poured with stirring onto 50 g of crushed ice, the aqueous acid was extracted with two 50 ml portions of methylene chloride. The methylene chloride was washed once with 50 ml water, dried over MgSO₄ and evaporated in vacuo to give 6,7-dihydro-benz[b]indeno[1,2-d]thiepin-8(8H)-one, mp 133°-138° C.

EXAMPLE II

By using the conditions of Example I, step 1 and in place of N-methylbenzamide, starting with

1. N-methylbenzamide
2. N-methylbenzamide
3. N,4-dimethylbenzamide
4. p-chloro-N-methylbenzamide
5. p-methoxy-N-methylbenzamide
6. N-methyl-benzamide
7. N-methyl-benzamide
8. N-methyl-benzamide
9. N-methyl-benzamide
10. 3,5-bis(trifluoromethyl)-N-methylbenzamide
11. 2-chloro-4-trifluoromethyl-N-methylbenzamide
12. N,3-dimethylbenzamide
13. 5-methoxy-N-methylbenzamide
14. 3-methoxy-N-methylbenzamide
15. 2-methoxy-N-methylbenzamide
16. N,5-dimethylbenzamide

and in place of 3,4-dihydro-1-benzothiepin-5-(2H)-one, starting with

1. 3,4-dihydro-1-benzoxaepin-5-(2H)-one
  2. 6,7,8,9-tetrahydro-1-benzocycloheptene-5-one
  3. 3,4-dihydro-1-benzothiepin-5-(2H)-one
  4. 3,4-dihydro-1-benzothiepin-5-(2H)-one
  5. 3,4-dihydro-1-benzothiepin-5-(2H)-one
  6. 7-methoxy-8-chloro-3,4-dihydro-1-benzothiepin-5-(2H)-one
  7. 7-methyl-8-methoxy-3,4-dihydro-1-benzothiepin-5-(2H)-one
  8. 7-chloro-8-methyl-3,4-dihydro-1-benzothiepin-5-(2H)-one
  9. 7,8-methylenedioxy-3,4-dihydro-1-benzothiepin-5-(2H)-one
  10. 3,4-dihydro-1-benzothiepin-5-(2H)-one
  11. 3,4-dihydro-1-benzothiepin-5-(2H)-one
  12. 6-chloro-3,4-dihydro-1-benzothiepin-5-(2H)-one
  13. 9-chloro-3,4-dihydro-1-benzothiepin-5-(2H)-one
  14. 9-methyl-3,4-dihydro-1-benzothiepin-5-(2H)-one
  15. 6-methyl-3,4-dihydro-1-benzothiepin-5-(2H)-one
  16. 3,4-dihydro-1-benzothiepin-5-(2H)-one,
- both the following intermediates of formula II and formula III are prepared:

FORMULA II

1. 2,3-dihydro-spiro[1-benzoxaepin-5(4H), 1'-phthalan]-3'-one
2. 6,7,8,9-tetrahydro-spiro[benzocycloheptene-5,1'-phthalan]-3'-one
3. 2,3-dihydro-6'-methyl-spiro[1-benzothiepin-5(4H), 1'-phthalan]-3'-one
4. 6'-chloro-2,3-dihydro-spiro[1-benzothiepin-5(4H), 1'-isobenzofuran]-3'-one
5. 2,3-dihydro-6'-methoxy-spiro[1-benzothiepin-5(4H), 1'-phthalan]-3'-one
6. 8-chloro-2,3-dihydro-7-methoxy-spiro[1-benzothiepin-5(4H), 1'-phthalan]-3'-one
7. 2,3-dihydro-8-methoxy-7-methyl-spiro[1-benzothiepin-5(4H), 1'-phthalan]-3'-one
8. 7-chloro-2,3-dihydro-8-methyl-spiro[1-benzothiepin-5(4H), 1'-phthalan]-3'-one
9. 2,3-dihydro-7,8-methylenedioxy-spiro[1-benzothiepin-5(4H), 1'-phthalan]-3'-one
10. 2,3-dihydro-5'7'-bis(trifluoromethyl)-spirop[1-benzothiepin-5(4H), 1'-phthalan]-3'-one
11. 4'-chloro-2,3-dihydro-6'-methyl-spiro[1-benzothiepin-5(4H), 1'-phthalan]-3'-one
12. 6-chloro-2,3-dihydro-5'-methyl-spiro[1-benzothiepin-5(4H), 1'-phthalan]-3'-one
13. 9-chloro-2,3-dihydro-7'-methoxy-spiro[1-benzothiepin-5(4H), 1'-phthalan]-3'-one
14. 2,3-dihydro-9-methyl-5'-methoxy-spiro[1-benzothiepin-5(4H), 1'-phthalan]-3'-one
15. 6-methyl-2,3-dihydro-4-methoxy-spiro[1-benzothiepin-5(4H), 1'-phthalan]-3'-one
16. 2,3-dihydro-7'-methyl-spiro[1-benzothiepin-5(4H), 1'-phthalan]-3'-one

35

FORMULA III

1. 2-[2,3,4,5-tetrahydro-5-hydroxy-1-benzoxepin-5-y1]-N-mentyl-benzamide
2. 2-[6,7,8,9-tetrahydro-5-hydroxy-5H-benzocyclohepten-5-y1]-N-methyl-benzamide
3. 2-[2,3,4,5-tetrahydro-5-hydroxy-1-benzothiepin-5-y1]-N,4-dimethyl-benzamide
4. 2-[2,3,4,5-tetrahydro-5-hydroxy-1-benzothiepin-5-y1]-N-methyl-4-chloro-benzamide
5. 2-[2,3,4,5-tetrahydro-5-hydroxy-1-benzothiepin-5-y1]-N-methyl-4-methoxy-benzamide
6. 2-[8-chloro-2,3,4,5-tetrahydro-5-hydroxy-7-methoxy-1-benzothiepin-5-y1]-N-methyl-benzamide
7. 2-[2,3,4,5-tetrahydro-5-hydroxy-8-methoxy-7-methyl-1-benzothiepin-5-y1]-N-methyl-benzamide
8. 2-[7-chloro-2,3,4,5-tetrahydro-5-hydroxy-8-methyl-1-benzothiepin-5-y1]-N-methyl-benzamide
9. 2-[2,3,4,5-tetrahydro-5-hydroxy-7,8-methylenedioxy-1-benzothiepin-5-y1]-N-methyl-benzamide
10. 2-[2,3,4,5-tetrahydro-5-hydroxy-1-benzothiepin-5-y1]-N-methyl-3,5-bis(trifluoromethyl)-benzamide
11. 2-[2,3,4,5-tetrahydro-5-hydroxy-1-benzothiepin-5-y1]-N-methyl-4-trifluoromethyl-6-chloro-benzamide
12. 2-[2,3,4,5-tetrahydro-5-hydroxy-6-chloro-1-benzothiepin-5-y1]-N,5-dimethyl-benzamide
13. 2-[2,3,4,5-tetrahydro-5-hydroxy-9-chloro-1-benzothiepin-5-y1]-N-methyl-3-methoxy-benzamide
14. 2-[2,3,4,5-tetrahydro-5-hydroxy-9-methyl-1-benzothiepin-5-y1]-N-methyl-5-methoxy-benzamide
15. 2-[2,3,4,5-tetrahydro-5-hydroxy-6-methyl-1-benzothiepin-5-y1]-N-methyl-6-methoxy-benzamide

16. 2-[2,3,4,5-tetrahydro-5-hydroxy-6-methyl-1-benzothiepin-5-yl]-N,3-dimethyl-benzamide

Following the procedure of Example I, step 2, and in place of 2,3-dihydro-spiro [1-benzothiepin-5-(4H)-1'-phthalan-3'-one, starting with the appropriate intermediate of formula II of step 1 of this example, the following products are obtained:

1. 6,7-dihydro-8H-benz[b]indeno[1,2-d]oxepin-8-one

2. 5,6-dihydro-dibenz[a,h]azulen-8(7H)-one

3. 6,7-dihydro-11-methyl-benz[b]indeno[1,2-d]thiepin-8(8H)-one

4. 11-chloro-6,7-dihydro-benz[b]indeno[1,2-d]thiepin-8(8H)-one

5. 6,7-dihydro-11-methyl-benz[b]indeno[1,2-d]thiepin-8(8H)-one

6. 3-chloro-6,7-dihydro-2-methoxy-benz[b]indeno[1,2-d]thiepin-8(8H)-one

7. 6,7-dihydro-3-methoxy-2-methyl-benz[b]indeno[1,2-d]thiepin-8(8H)-one

8. 2-chloro-6,7-dihydro-3-methyl-benz[b]indeno[1,2-d]thiepin-8(8H)-one

9. 6,7-dihydro-2,3-methylenedioxy-benz[b]indeno[1,2-d]thiepin-8(8H)-one

10. 6,7-dihydro-10,12-bis trifluoromethyl-benz[b]indeno[1,2-d]thiepin-8(8H)-one

11. 9-chloro-6,7-dihydro-11-trifluoromethyl-benz[b]indeno[-d]thiepin-8(8H)-one

12. 1-chloro-6,7-dihydro-10-methyl-benz[b]indeno[1,2-d]thiepin-8(8H)-one

13. 4-chloro-6,7-dihydro-12-methoxy-benz[b]indeno[1,2-d]thiepin-8(8H)-one

14. 6,7-dihydro-4-methyl-10-methoxy-benz[b]indeno[1,2-d]thiepin-8(8H)-one

15. 6,7-dihydro-1-methyl-9-methoxy-benz[b]indeno[1,2-d]thiepin-8(8H)-one

16. 6,7-dihydro-12-methyl-benz[b]indeno[1,2-d]thiepin-8(8H)-one

EXAMPLE III

This example describes the procedure for preparing compounds of formula I following the procedure of reaction schemes A, b₁, b₂ and C. The conditions of Example I, steps 1 and 2, are followed, with the exception that the compounds of the hydrolysis reaction mixture of step 1 (Ex. I) are not separated but instead are refluxed in anhydrous tetrahydrofuran to convert the intermediate of formula III into the intermediate of formula II.

Step 1

By using the conditions of Example I, step 1 and in place of N-methyl-benzamide and 3,4-dihydro-1-benzothiepin-5-(2H)-one starting with

1. 3,4-methylenedioxy-N-methylbenzamide

2. 3,4-dihydro-1-benzoxaepin-5-(2H)-one, a reaction mixture of the following intermediates of formula II and formula III respectively are prepared:

1. 2,3-dihydro-5',6'-methylenedioxy-spiro[1-benzoxepin-5(4H)-1'-phthalan]-3'-one

2. 2-[2,3,4,5-tetrahydro-5-hydroxy-1-benzoxepin-5-yl]-N-methyl-4,5-methylenedioxy-benzamide

Step 2

The reaction mixture of step 1 of this example is refluxed in anhydrous tetrahydrofuran, and the resulting 2,3-dihydro-5,6'-methylenedioxy-spiro[1-benzoxepin-5(4H)-1'-phthalan]-3'-one is treated following the procedure of Example I, step 2, to obtain the product, 6,7-dihydro-10,11-methylenedioxybenz[b]indenod[1,2-d]thiepin-8-(8H)-one.

What is claimed is:

1. A compound of the formula

15

20

25

wherein R₁ is hydrogen, halo having an atomic weight of

19 to 36, or lower alkoxy having one to four carbon atoms;

R₂ and R₄ are independently hydrogen, lower alkyl having one to four carbon atoms, lower alkoxy having one to four carbon atoms or trifluoromethyl;

R₃ is hydrogen, halo, having an atomic weight of 19 to 36, lower alkyl having one to four carbon atoms, lower alkoxy having one to four carbon atoms, or trifluoromethyl;

R₅ and R₈ are independently hydrogen, halo having an atomic weight of 19 to 36, or lower alkyl having one to four carbon atoms;

R₆ and R₇ are independently hydrogen, halo having an atomic weight of 19 to 36, lower alkyl having one to four carbon atoms, or lower alkoxy having one to four carbon atoms;

R₁ and R₂ or R₂ and R₃ or R₃ and R₄ together are methylenedioxy; or

R₅ and R₆ or R₆ and R₇ or R₇ and R₈ together are methylenedioxy; and X is -CH₂-, S or O;

provided that 1. maximum number of substituents on each of rings A and D is two, and 2. there are no adjacent trifluoromethyl groups.

2. The compound according to claim 1 which is 6,7-dihydro-benz[b]indenod[1,2-d]thiepin-8(8H)-one.

3. The compound according to claim 1 which is 6,7-dihydro-8H-benz[b]indenod[1,2-d]oxepin-8-one.

60 4. The compound according to claim 1 which is 5,6-dihydro-dibenz[a,h]azulen-8(7H)-one.
